UNITED STATES PATENT OFFICE.

ROBERT H. RICE, OF CHICAGO, ILLINOIS, ASSIGNOR TO SOLAR PRODUCTS CO., OF CHICAGO, ILLINOIS, A CORPORATION OF ILLINOIS.

DISPLAY CARTON.

Application filed September 28, 1925. Serial No. 59,050.

My invention relates to cartons usually constructed of heavy paper-board and which are adapted to be used as shipping cartons, and then by certain simple folding operations, as display cartons.

The object of my invention is provide such a carton having the necessary strength to withstand the handling it receives while in transportation, and which may be readily converted into a display carton.

It is also an object of my invention to provide such a carton which will have ample space for advertising matter, which will be visible when the carton is opened up for display purposes. Other objects and the advantages of my invention will appear when reference is had to the following specification, when considered in connection with the accompanying drawings, wherein I have illustrated a selected embodiment, and in which:—

Fig. 1 is a perspective view of my improved carton as it appears when opened to serve as a display carton.

Fig. 2 is a perspective view showing my improved carton as it appears as a shipping carton, and

Fig. 3 is a plan view of the blank used in forming my carton.

Referring now to the drawings, my improved carton comprises front and back walls 5 and 6 respectively, and side walls 7 and 8. Bottom closure flaps 9, 10, 11 and 12 are formed integrally with their respective walls and top closure flaps 13, 14, 15 and 16 are likewise formed integrally with their respective walls.

As indicated most clearly in Fig. 3, the top and bottom closure flaps are cut as indicated at 17 and 18 respectively to correspond in width to their respective sides and the blank is slitted as indicated at 19 and 20. The last named slits 19 and 20 are disposed in the front corners of the carton and the front and side walls are taped together along the said slits as indicated by the gummed tapes 22 and 23, this construction being for a purpose which will hereinafter be explained.

The blank is further scored as indicated at 24, 25 and 26 in order to render it easily folded into rectangular shape to form the body or side walls of the carton. When so formed or folded, the edges 27 and 28 of the blank may be joined together by means of a strip of gummed tape indicated at 29.

Horizontal scoring along the lines 30 and 31, extending the entire length of the blank, determine the top and bottom edges of the respective walls and provide means whereby the top and bottom closure flaps may be easily folded inwardly.

The construction of the carton so far described is the usual structure for rectangular cartons, with the exception of the slitting indicated at 19 and 20, and taping indicated at 22 and 23, and except that the rear top flap 16 is considerably wider than the front top flap 14. When the carton is folded, the side, top and bottom flaps are first turned inwardly and then the front and back top and bottom flaps are turned inwardly over the aforementioned side flaps, and a strip of gummed tape 32, (Fig. 2) may then be placed over the adjacent edges of the two top flaps, and a like strip of tape may be placed over the adjacent edges of the two bottom flaps to seal the carton.

To render my carton adaptable for display purposes, I score the front wall along a horizontal line 33 extending between the lower ends of the slits 19 and 20 and preferably located somewhat below the centre of the front wall. The side walls are scored along inclined lines extending upwardly and rearwardly from the ends of the score 33 to the upper rear corners of the side walls, as indicated at 34 and 35. When the carton is to be opened to display its contents, the strip of tape 32 is cut to open the top of the carton and the tape strips 22 and 23 on the front corners of the carton are also cut from the top downwardly to the junctures of the score 33 with the scores 34 and 35. When this is done, the rear top flap 16 may be opened up and left in an upwardly extending position, and the upper portion of the front wall 5 may be turned outwardly along the score 33 into the position shown in Fig. 1, to form downwardly extending inclined flap 41. The upper portions of the side walls may then be turned outwardly along the scored lines 34 and 35 into the position shown in Fig. 1 to form outwardly extending inclined flaps 42 and 43.

The top closure flaps 13 and 15 may conveniently be folded downwardly along the horizontal score mark 30 or these flaps may be further scored along diagonal lines as indicated by the lines 36 and 37 to render a portion thereof easily turned down, forming wings 44 and 45 having an edge thereof ad-

10 jacent the respective rear corners of the carton where they may be secured by means of strips of gummed tape as indicated at 38 and 39, (Figs. 1 and 3). The front wall 5 may be maintained in the position illustrated in Fig. 1, by turning the narrow front top flap 14 inwardly, and securing it in this position by means of a strip of gummed tape 40, secured to it and to the bottom of the carton 15 as clearly shown in Fig. 1.

11 I find it is convenient to supply cartons of the above description with fastening tapes secured to the top flaps 13, 14 and 15 as illustrated in Fig. 3, which may be used as 15 above described by merely moistening the gummed surface, and then sticking them to the back walls or bottom, as the case may be, when the carton is opened for display purposes.

20 While I have shown and described gummed tape strips as a means for fastening the various flaps in display position, it is to be noted that various other means for fastening may be employed or the various flaps may be left un- 25 secured.

21 When the flaps 16, 41, 42 and 43 are opened and outturned as described, the carton is provided with an inclined top opening through which the contents of the carton will partially 30 project so as to be effectively displayed and rendered readily accessible. Also, advertising matter on the inner surfaces of these flaps will be attractively displayed above, in front of and on opposite sides of the goods exposed 35 through the inclined open top portion of the carton.

22 Instead of slitting the front corners as at 19 and 20, I may simply continue the scores 24 and 25 upwardly the entire height of the sides 40 whereby the strength of the carton is not affected to any extent, and which also enables the corners to be quite easily slit in when the box is to be opened for display purposes.

23 I am aware that changes in the form and 45 proportion of parts may be made in the construction of my carton without departing from the essence of the invention, and I reserve the right to make all such changes as fairly fall within the scope of the following 50 claims.

24 I claim as my invention:

25 1. A display carton having front, side, and rear walls and top and bottom closure flaps, said front wall being scored along a substan- 55 tially horizontal line, and said side walls being scored along upwardly and rearwardly inclined lines to form the upper portion of the front wall and the upper forward portions of the side walls into flaps that are adapted to be 60 separated and turned outwardly for display purposes.

26 2. A display carton having front, side, and rear walls, and top and bottom closure flaps extending from said side walls, said front 65 wall being scored on a substantially horizon-

tal line, and said side walls being scored along upwardly and rearwardly inclined lines to form flaps adapted to be turned outwardly for display purposes, and the side top flaps being scored along a line extending diagonally from the inner edges thereof to the outer edges thereof, to form wings adapted to be turned downwardly to dispose an edge thereof adjacent the corresponding sides of the carton 70 for fastening purposes. 75

3. A carton comprising front, side, and rear walls, and top and bottom closure flaps, said front wall being scored on a substantially horizontal line, and said side walls being scored on upwardly and rearwardly inclined 80 lines to form the upper portion of the front wall and the upper forward portions of the side walls into flaps that are adapted to be turned outwardly for display purposes, and means for maintaining said flaps outturned in 85 inclined position.

4. A carton comprising front, side, and rear walls, and top and bottom closure flaps, said front wall being scored on a substantially horizontal line, and said side walls being 90 scored along upwardly and rearwardly inclined lines to form flaps adapted to be turned outwardly for display purposes, means for maintaining the front flap so turned, comprising the front top closure flap, and means for 95 attaching said closure flap to the bottom of the carton, and means for maintaining the side flaps so turned, comprising the respective side top closure flaps and wings formed thereon by means of scoring extending diagonally from 100 the inner edges of the said flaps to the outer edges thereof, said wings being adapted to be turned downwardly to dispose an edge thereof adjacent the corresponding side walls of 105 the carton, and means for fastening said wings to the side walls of the carton. 110

5. A carton comprising front, side, and rear walls, and the top and bottom closure flaps, said front wall being scored adjacent the central portion thereof along a substan- 110 tially horizontal line, and said side walls being scored along inclined lines extending upwardly and rearwardly from points adjacent the ends of such horizontal line to the upper edges of the carton to form the upper portion 115 of the front wall and the upper forward portions of the side walls into flaps that are adapted to be outturned for display purposes.

6. A display carton comprising front, side, and rear walls and top and bottom closure 120 flaps, said front wall being scored in a sub- stantially horizontal line and said side walls being scored along inclined lines extending upwardly and rearwardly from the ends of such horizontal line to form flaps adapted to 125 be turned outwardly for display purposes, the front side corners of said carton being slit downwardly from the top to a point substantially at the juncture of the said scoring on said front and side walls and the front 130

and side walls being taped together along such slits.

7. A display carton comprising front, side, and rear walls and top and bottom closure flaps, said front wall being scored on a substantially horizontal line, and said side walls being scored along upwardly and rearwardly inclined lines to form flaps adapted to be turned outwardly for display purposes, 10 means for maintaining the front flap so turned comprising the front top closure flap, and a strip of gummed tape secured to said top closure flap, and adapted to be attached to the bottom of the carton, and means for 15 maintaining the side flaps so turned comprising the respective side top closure flaps and wings formed thereon by means of scoring extending diagonally from the inner edges thereof to the outer edges thereof, said wings 20 being adapted to be turned downwardly to dispose an edge thereof adjacent the walls of the carton, and a strip of gummed tape secured to the said wings, and adapted to be attached to the walls of the carton.
- 25 8. A display carton comprising a tubular box body formed of front, rear and side walls and pairs of top and bottom closure flaps, said front wall being horizontally scored and said side walls scored along upwardly and 30 rearwardly inclined lines, the upper portions of said front and side walls above said scores being adapted to be separated and out-turned into display flaps, the inner surfaces of said portions and of the top rear closure flap being adapted to bear advertising matter and, 35 when opened, to expose the contents of the carton through the inclined top opening and present the inner display surfaces in front

and on opposite sides of and above such opening, substantially as described. 40

9. A display carton having front, rear and side walls, and top and bottom closure flaps, said front wall being scored adjacent the central portion thereof along a substantially horizontal line and said side walls being 45 scored along inclined lines extending upwardly and rearwardly from points adjacent the ends of said horizontal line to the upper edges of the carton, to permit the upper portion of the front wall and the upward forward portions of the side walls to be out-turned when separated, and means connecting the adjacent edges of said portions adapted to be severed to permit the outturning thereof for display purposes, substantially 50 55 as described.

10. A display carton comprising a tubular, collapsible box body formed of front, rear and side walls having hinge connections at the vertical corners of the box body and pairs of top and bottom closure flaps hinged to said walls, said front wall being horizontally scored and said side walls scored along upwardly and rearwardly inclined lines to enable the upper portion of the front wall and the upper forward portions of the side walls to be out-turned into display flaps when the hinge connections between them are severed and thereby expose the contents of the carton through an inclined top opening and expose 70 the inner surfaces of said flaps in front and on opposite sides of such opening, substantially as described. 60 65
